United States Patent Office

Des. 210,341

Patented Feb. 27, 1968

210,341

PURSE

Ludwig S. Schlessinger, New York, N.Y., assignor to Bond Street Ltd.

Filed May 16, 1966, Ser. No. 2,309

Term of patent 7 years

(Cl. D87—3)

FIG. 1

FIG. 2

FIG. 3

FIG. 4

FIG. 1 is a front perspective view of a purse showing my new design in closed condition;

FIG. 2 is a rear perspective view thereof in closed condition;

FIG. 3 is a front perspective view thereof in an open condition;

FIG. 4 is another front perspective view thereof in a different open position.

I claim:

The ornamental design for a purse, as shown.
